US00D951607S

(12) United States Design Patent (10) Patent No.: US D951,607 S
(45) Date of Patent: * May 17, 2022

(54) FOOTWEAR

(71) Applicant: Bottega Veneta S.R.L., Montebello Vicentino (IT)

(72) Inventor: Daniel Harry Lee, Milan (IT)

(73) Assignee: BOTTEGA VENETA S.R.L., Montebello Vicentino (IT)

() Term: 15 Years

(21) Appl. No.: 29/763,437

(22) Filed: Dec. 22, 2020

(30) Foreign Application Priority Data

Jul. 8, 2020 (EM) 008035844-0005

(51) LOC (13) Cl. 02-04

(52) U.S. Cl.

(57) CLAIM

The ornamental design for footwear, as shown and described.

DESCRIPTION

FIG. 1 is a top perspective view of a footwear showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Color or shading, including color or shading contrasts or gradients, form no part of the claimed design.

1 Claim, 7 Drawing Sheets
